CAN OPENING DEVICE

John M. Hothersall, Brooklyn, N. Y., assignor to
American Can Company, New York, N. Y., a corporation of New Jersey

Application April 23, 1937, Serial No. 138,657

3 Claims.

(Cl. 30—16)

The present invention relates to can opening devices and has particular reference to a one-piece opener of simple construction which is adapted to be applied to an end of a can adjacent the seam or rim connecting the end with the body, for forming a pouring opening in the can end and for shaping the end seam or rim adjacent the opening into a pouring spout to facilitate dispensing of the can contents.

An object of the present invention is the provision of a simple one-piece can opening and spout forming device which is adapted to be easily applied to an end of a can adjacent its end seam or rim and by a simple puncturing and rocking movement, using the can end seam or rim as a fulcrum, simultaneously in one sweeping movement, to re-shape the puncture opening, the can end, the end seam or rim and a portion of the can body adjacent the seam to provide a cooperating pouring opening and spout which will permit dispensing of the can contents in an unrestricted and full stream when the can is tilted into pouring position.

Another object is the provision of a simple one-piece can opening and spout forming device of the character described having a puncturing point which enters the can end adjacent the seam to provide a pouring opening and to position the device so that a rocking movement on the engaged seam as a pivot bends over the seam while pressing in on the side wall just beneath to form the engaged wall and seam into a pouring spout.

Numerous other objects and advantages of the invention will be apparent as it is better understood from the following description, which, taken in connection with the accompanying drawing, discloses a preferred embodiment thereof.

Referring to the drawing:

Figure 1 is a rear elevation of a can opening device embodying the instant invention;

Fig. 2 is a detail showing a front elevation of the lower end of the device;

Fig. 3 is an end plan view taken substantially along a plane indicated by the line 3—3 in Fig. 2;

Fig. 4 is a side elevation of the opener and a fragmentary sectional view of the upper end of a can showing the opener in position on the can at the beginning of the opening operation;

Fig. 5 is a view similar to Fig. 4 and showing the upper end of a can in section with the opening device in position at the completion of the opening operation; and

Fig. 6 is a perspective view of a can showing a

front view of the opening and the shape of the pouring spout made by the opener.

A preferred embodiment of the instant invention is illustrated in the drawing and includes a flat rectangular elongated handle member 11 preferably made of medium weight rectangular bar stock. The lower end of the handle is viewed in Figs. 1, 2 and 4, terminates in a blunt end section 12. Just above this blunt end section a portion of the handle is cut away and turned back 10 on itself to a position substantially parallel with but spaced away from the face of the handle to form a cutter 14. The space between the back of the cutter and the face of the handle is preferably slightly greater than the thickness of the 15 standard end seam or rim of an ordinary tin can, this thickness usually being a standard dimension in can making practice. The cutter is formed into an outwardly curved cross-section as indicated at 15 in Fig. 3. The lower end of the cutter 20 extends below the blunt end section 12 of the handle 11 and is sharpened into a cutting point 16.

The upper end of the handle 11 is preferably bent at substantially right angles as shown in Fig. 4 to provide a head section 17 for use in applying a pressure on the device.

The opening device is preferably applied to a can, as exemplified by the can 21 shown in Fig. 1. It is first placed in a vertical position as shown 30 in Fig. 4 with the rear wall of the cutter 14 engaging the can end seam or rim, indicated by the numeral 22, and with the point of the cutter resting on the can end (marked 23). In this position the blunt end 12 of the handle 11 is over 35 the top of but is disposed outwardly beyond the can seam 23.

While in this position the cutter is pressed down or a sharp blow may be struck on the right angle section 17 at the upper end of the handle 11. This drives the cutter down into the can end 23, puncturing the same while moving the blunt end 12 of the handle down alongside of the end seam. In lowered position its lower end projects below the seam (see dotted lines in Fig. 4). 40 The opening thus made in the can end is not sufficient to provide a pouring opening but in this preliminary stage the opening does create an anchor hold for temporarily retaining the device 45 in vertical position.

The completion of the forming of a pouring opening and the shaping of a pouring spout may now be made at one and the same time by a mere rocking or pivoting of the applied device by moving the handle 11 in a clock-wise direction 50

(as viewed in Fig. 4) using the can seam as a fulcrum. This action presses the blunt end 12 of the handle against the side wall of the can just under the end seam causing the wall to be forced inwardly as shown in Fig. 5. At the same time the rear wall of the cutter presses downwardly on the can seam and this bends over the engaged section of the seam. This simple combined action re-shapes only a small part of the can side wall and a small part of the end seam and forms a pouring spout 25 (Fig. 6).

Simultaneously with the formation of the pouring spout the forward face of the cutter 14 presses upwardly on the bottom or inner surface of the can end 23. This slightly elongates the hole made by the cutter and at the same time bends the can end adjacent the hole into an inverted channel having an arch cross-section thereby forming a raised or elevated pouring opening 26 (Figs. 5 and 6). This opening is shaped, in cooperation with the pouring spout 25, to discharge the can contents in a smooth running and steady stream when the opened can is tilted into pouring position.

25 If desired a vent hole 27 (Fig. 6) may be made in the can end with the point of the cutter. It has been found that some liquids flow out through the opening with greater speed and in a more steady stream if such a vent hole is provided.

30 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

40 1. A one-piece can opening and spout forming device, comprising a flat substantially rectangular handle member, an elongated cutter comprising a struck out part of the flat surface of said handle member adjacent one end thereof and extending parallel to but spaced therefrom a distance slightly greater than the thickness of the seam joining the can and its end, said cutter depending below the can engaging end of said handle member and having a puncturing point adapted to 45 enter into the can end adjacent the seam when the device is applied to the can with the can seam disposed within the space between the handle and cutter, whereby the engaged seam and the end and side can walls adjacent thereto 50 are re-shaped into a pouring spout by a rocking movement of said handle outwardly and downwardly to cause the said cutter to elevate and reshape the engaged part of the can end while enlarging and reshaping the opening made in the 55 can end by insertion of said cutter to provide a free flowing discharge opening, the elongated configuration of said cutter serving to increase the depth of said spout and its longitudinal dimension radially of the can end.

60 2. A can opening and spout forming device comprising an elongated flat substantially rec-

tangular handle member terminating at one end in a blunt end section disposed in the plane of the handle member, a portion of the handle member adjacent said blunt end section being cut out and bent reversely to depend a material predetermined distance below said blunt end section to constitute a cutting element spaced from and disposed in a plane substantially parallel to said handle member, said depending cutting element being designed to be moved vertically to puncture a can end adjacent the rim connecting the end with the can body with the blunt end section of the handle member engaging over said rim and the cutting element projecting vertically within and adjacent the inner side wall of the can, and an outward rocking movement of more than 90 degrees imparted to said handle member downwardly with respect to the can and using the can rim as a fulcrum, will cause the cutting element and the blunt end section of the handle to reshape the can end, the rim and a side wall of the can body adjacent the opening, into a cooperating pouring opening and elongated spout arched above said can end for freely dispensing the can contents when the can is tilted into pouring position.

3. A can opening and spout forming device comprising an elongated flat substantially rectangular handle member terminating at one end in a blunt end section disposed in the plane of the handle member, an angularly disposed head section on the opposite end of said handle member for applying longitudinal pressure thereto, an intermediate portion of the handle member adjacent said blunt end section being struck out and bent reversely to depend a material predetermined distance below said blunt end section to constitute an elongated cutting element terminating in a sharp piercing point spaced from and disposed in a plane substantially parallel to said handle member, said depending cutting element being designed to be moved vertically when pressure is applied to said head section to penetrate a can end adjacent the rim connecting the end with the can body with the blunt end section engaging over said rim in fulcrum position and extending down adjacent the outer can body wall when the can end is punctured, with said cutting element projecting vertically within and adjacent the inner side wall of the can, and an outward rocking movement of more than 90 degrees imparted to said handle member downwardly with respect to the can and using the can rim as a fulcrum, will bring said blunt end section into bending engagement with the can body beneath said rim while simultaneously causing said cutting element to reshape the puncture opening, the can end and the rim adjacent the opening, into a cooperating pouring opening and spout for readily dispensing the can contents in a full and steady stream when the can is tilted to pouring position, the elongated configuration of said cutting element increasing the depth of said spout and its longitudinal dimension radially of the can end.

JOHN M. HOTHERSALL.
